UNITED STATES PATENT OFFICE.

FRED HOLMES REES, OF ELMIRA, NEW YORK.

LACING-HOOK.

SPECIFICATION forming part of Letters Patent No. 650,481, dated May 29, 1900.

Application filed October 23, 1899. Serial No. 734,470. (No model.)

To all whom it may concern:

Be it known that I, FRED HOLMES REES, a resident of Elmira, in the county of Chemung and State of New York, have invented certain new and useful Improvements in Lacing-Hooks; and I do hereby declare the following to be a full, clear, and exact description of the invention, such as will enable others skilled in the art to which it pertains to make and use the same.

The invention relates to hooks for lacing shoes, gloves, gaiters, and leggings, and for other like purposes; and it has for its object to provide a simple, efficient, and durable article that will hold lacing in a yielding, elastic, and sufficiently-firm manner, whereby a satisfactory laced closure can be produced and maintained without uncomfortably and injuriously binding the ankle, wrist, or other part of the person upon which the laced article is worn.

The invention consists in the construction hereinafter described and pointed out.

In the accompanying drawings, Figure 1 is a front elevation, partly in section. Fig. 2 is a longitudinal section. Fig. 3 is a perspective of a spring. Fig. 4 is a perspective of a lacing-protector to cover the spring. Fig. 5 is a similar view of a spring provided integrally with lacing-protectors. Fig. 6 is a perspective of the device made from a single piece of wire.

Numerical 1 denotes the shank of a hook, which shank is preferably tubular, as indicated, and is virtually an eyelet, whereby the hook is fixed to any desired article, as customary.

2 is a pin or rivet fixed transversely in the upper end of the eyelet-shank.

3 denotes a spring, preferably of steel wire. 40 Each end of the spring is provided with a coil 4, surrounding the pin and having an end or extension 5 bearing upon the hook-shank or eyelet, as represented. The main part of the wire is bent to form a loop or frame 6, having side members 6', joined by a straight member 7.

8 denotes a groove or way formed in the inner face of the point 9 of the hook. Said groove receives the member 7, which can 45 freely play back and forth therein between the positions indicated by the full and dotted lines in Fig. 2. When not compressed, the

spring-frame is situated as indicated by full lines in said figure; but under pressure it may be driven back to the position of the 55 dotted lines. In practice this spring may have a movement of about one-eighth of an inch, and since a like yielding movement may be produced in its fellow immediately opposite there can be an expansion and contraction of 60 about one-fourth of an inch between each pair of opposite hooks, and as this is true of every pair of oppositely-adjacent hooks it is obvious that the article laced is held upon the person in manner to easily yield to variation of size and change of form caused by 65 muscular exertion, heat and cold, and variable blood circulation. This in a shoe, for example, gives an ease and comfort such as pertains to the so-called "Congress" shoe or 70 to a low shoe without the objectionable features of either. The ankles inclosed by shoes laced by the aid of the improved hooks are free to move, while they are closely covered.

The form of the spring is such that it readily receives the lacing when wound about the hooks in the usual manner, but is not liable to accidentally catch other objects, nor is it liable to become disarranged, bent, or malformed, as are the coiled springs which have 80 lacing-buttons on their free ends.

To prevent the lacing from being cut or worn by the spring-arms, it is preferred to flatten and round them, as indicated at 10 in Fig. 5. These comparatively-wide portions of the 85 spring present curved surfaces to the lacing and provide that it may slip easily without injury by chafing.

In some cases a separate cover 11 having bent edges 12 to embrace the side arms of the 90 spring-frame may be employed as an anti-friction-guard, though the form first described has the advantage of cheapness and simplicity.

It is contemplated in some cases to make the 95 hook and spring integrally of a single piece of wire bent into suitable form, as shown in Fig. 6. Such form is not preferred, but it may have a novel ornamental effect, particularly when made of precious metal, and it embodies the same principle of operation.

13 denotes extensions for securing the article to a fabric or to leather, and 14 the hook proper.

15 denotes spring-coils, and 16 is the spring-frame.

Having thus described my invention, what I claim is—

5. 1. A lacing-hook having a spring extending from its shank to its outer part and adapted to directly receive lacing wound about the hook.

10. 2. A lacing-hook having a spring extending from its shank to its outer part and adapted to directly receive lacing wound about the hook, said spring having side arms connected by a cross bar or member.

15. 3. A lacing-hook having a spring extending from its shank to its outer part and adapted to directly receive lacing wound about the hook, said spring having side arms connected by a cross bar or member, and a recess in the outer part 9 of the hook to receive said cross-bar.

20. 4. A lacing-hook having a spring extending from its shank to its outer part and adapted to directly receive lacing wound about the hook, said spring having a coil in the hook-shank.

25. 5. A lacing-hook having a spring extending from its shank to its outer part and adapted to directly receive lacing wound about the hook, said spring having a coil in the hook-shank, and an extension beyond the coil to 30 bear on the shank and hold the spring to its work.

35. 6. A lacing-hook having a spring extending from its shank to its outer part and adapted to directly receive lacing wound about the hook, said spring having a rounded guard to prevent chafing the lacing.

40. 7. A lacing-hook having a spring extending from its shank to its outer part and adapted to directly receive lacing wound about the hook, said spring having a rounded guard integral with the spring-arms.

In testimony whereof I have signed this specification in the presence of two subscribing witnesses.

FRED HOLMES REES.
